UNITED STATES PATENT OFFICE.

MEYER MARGOLIN AND ALEKS KARRON, OF NEW YORK, N. Y.

GRATE.

No. 855,795.

Specification of Letters Patent.

Patented June 4, 1907.

Application filed March 14, 1906. Serial No. 305,940.

To all whom it may concern:

Be it known that we, MEYER MARGOLIN and ALEKS KARRON, citizens of the United States, residing at New York, in the county 5 of New York and State of New York, have invented certain new and useful Improvements in Grates, of which the following is a specification, such as will enable those skilled in the art to which it appertains to make and 10 use the same.

This invention relates to grates for use in cooking stoves, cooking ranges and other heaters of various kinds and classes; and the 15 object thereof is to provide an improved device of this class which is particularly designed for use for the purpose of starting a coal, wood or other fire, but which may also be employed if desired as a fire grate or burner in stoves, ranges and other heaters 20 employing gas, vapor, oil or similar substances as a heat producing medium.

The invention is fully disclosed in the following specification, of which the accompanying drawing forms a part, in which the 25 separate parts of our improvement are designated by suitable reference characters in each of the views, and in which:—

Figure 1 is a plan view of a circular grate involving our invention and showing the 30 same mounted in a fire-box or casing, the latter being in section and a part of the grate attachments or connections being also in section; Fig. 2 a plan view of a rectangular grate made according to our invention; Fig. 35 3 a section on the line 3—3 of Fig. 1; and, Fig. 4 a partial section on the line 4—4 of Fig. 1.

In the practice of our invention as shown in Figs. 1, 3 and 4, we provide a grate *a* 40 which is circular in form and which is composed of a bottom member *a*² and top member *a*³, said parts or members being secured together by means of bolts or screws or in any desired manner as shown at *a*⁴. The 45 grate *a* comprises an annular rim portion and transversely arranged bars *a*⁵, and the top and bottom portions *a*² and *a*³ in this respect are formed in the same manner, but the bottom portions *a*⁶ of the bars *a*⁵ are preferably 50 of less transverse width than the top portions *a*⁷ of said bars, and the bottom portions of said bars are hollow, and formed in the top edges thereof are ports or passages *a*⁸ through which, in practice, the gas or other 55 medium escapes.

The bottom part of the annular outer por-

tion of the grate *a* is also preferably narrower in transverse section than the top portion thereof as clearly shown in Fig. 3, and the ports or passages *a*⁸ are formed in the inner 60 side thereof, at the top thereof, and may be formed in the outer side thereof, if desired; and by forming the top of the outer annular portion of the grate and of the bars *a*⁵ wider than the bottom portion thereof, we provide 65 means whereby dust, dirt, ashes and the like are prevented from entering the ports or passages *a*⁸ through which the gas escapes.

In Fig. 1, we have shown the grate *a* mounted in a casing *b*, which may form the 70 base of a stove or heater or the fire box thereof, and the grate is provided with trunnions *c* which pass through suitable bearings *b*² with which the casing *b* is provided, and one of the trunnions *c* is tubular in form as shown 75 at *c*² and the pipe *d* is connected therewith through one of the bearings *b*² as clearly shown in Fig. 1, and the gas or other material to be burned in the grate *a* is supplied to said grate through the pipe *d*. 80

In Fig. 2, we have shown a modification of the grate *a* which is similar in all respects to said grate *a*, except in the form thereof, the grate shown in Fig. 2 being angular or rectangular in form. 85

It will be observed that the bars of the grate or the spaces therein are all in communication, and all in communication with the space within the outer or frame portion of the grate, and gas or other material admitted 90 through the pipe *d* is free to circulate around the grate and through the various bars thereof.

Our improved grate is particularly adapted for use as a fire starter in cooking stoves, 95 ranges and other heaters of various kinds and classes which employ coal or wood as the main heating medium, but it will be apparent that our improved grate may also be used as a gas, or vapor, or oil burning grate 100 in stoves, ranges and other heaters which employ these materials only for heating purposes.

Having fully described our invention, what we claim as new and desire to secure by Letters Patent, is:—

A grate comprising a frame and parallel bars, said frame and bars being composed of top and bottom members secured together, the bottom members of the bars being hollow 110 to form gas passages and the frame being provided with a passage which communicates

with the passages in said bars, the top portions of the bottom members of said bars being provided with side ports or passages which are covered and protected by the top
5 members of said bars, and the inner walls of the frame being also provided with ports or passages which communicate with the spaces therein and which are covered and protected by the top member of the frame.

In testimony that we claim the foregoing ¹⁰ as our invention we have signed our names in presence of the subscribing witnesses this 12th day of March 1906.

MEYER MARGOLIN.
ALEKS KARRON.
